UNITED STATES PATENT OFFICE.

FRANK H. FRISSELL, OF MIDDLETOWN, CONNECTICUT.

MACHINE-GUN FEED-BELT.

1,247,810.

Specification of Letters Patent. Patented Nov. 27, 1917.

Application filed March 2, 1917. Serial No. 151,909.

To all whom it may concern:

Be it known that I, FRANK H. FRISSELL, a citizen of the United States, residing at Middletown, in the county of Middlesex and State of Connecticut, have invented a new and useful Improvement in Machine-Gun Feed-Belts; and I do hereby declare the following, when taken in connection with the accompanying drawings, and the characters of reference marked thereon, to be a full, clear, and exact description of the same, and which said drawings constitute part of this application, and represent, in—

Figure 1 a broken plan view of one form which a machine-gun feed belt constructed in accordance with my invention may assume.

Fig. 2 a view thereof on the line 2—2 of Fig. 1.

Fig. 3 a sectional view thereof on the line 3—3 of Fig. 1.

Fig. 4 a view of one of the concealed belt-stays detached.

Fig. 5 a corresponding view of a combined belt-stay and fender.

Fig. 6 a schematic edge view on an enlarged scale to show the crossing of the warp-threads from side to side of the fabric for the production of the woven alternating cartridge-pockets and belt-stay pockets.

Fig. 7 a detached view of one of the modified forms which the belt-stays may assume.

Fig. 8 a similar view of one of the modified forms which the combined belt-stay and fender may assume.

Fig. 9 a detached view of another modified form which the belt-stay may assume.

Fig. 10 a corresponding view of another modified form which the combined stay and fender may assume.

My invention relates to an improved woven machine-gun feed belt, the object being to produce at a low cost for labor and material, a simple, effective and durable belt characterized by cartridge-receiving pockets alternating with stay-receiving pockets, whereby the belt-stays are housed, as it were, within the belt, leaving the exterior surface thereof relatively smooth and reducing the danger of its fouling in use, and also reducing the danger of its threads being cut upon the edges of the stays.

With these ends in view, my invention consists in a machine-gun feed belt having

alternating cartridge-receiving and stay-receiving pockets. 55

My invention further consists in a machine-gun feed belt having woven alternating cartridge-receiving and stay-receiving pockets. 60

My invention further consists in a machine-gun feed belt having woven alternating cartridge-receiving pockets and stay-receiving pockets, the cartridge-receiving pockets being reduced in diameter adjacent 65 to the inner edge of the belt and the stay-receiving pockets being closed at the outer edge of the belt, and means applied to the belt for closing the open ends of the stay-receiving pockets at points between the reduced ends of the cartridge-receiving pockets. 70

My invention further consists in a machine-gun feed belt having alternating cartridge-receiving and stay-receiving pockets, 75 in combination with yielding stays located in the said stay-receiving pockets and exerting pressure upon the cartridges in the cartridge-receiving pockets for retaining them in place. 80

My invention further consists in a machine-gun feed belt having certain details of construction and combination of parts as will be hereinafter described and pointed out in the claims. 85

In carrying out my invention as herein shown, I produce in a loom suitably set up for the purpose, a woven belt having alternating cartridge-receiving and stay-receiving pockets 4 and 5, the former being adapted in size for the reception of standard cartridges, and the latter being adapted in size for the reception of belt-stays to prevent the belt from collapsing edgewise. As herein shown and preferably, the warp-threads 6 of the belt-fabric, are crossed from side to side of the belt at regularly spaced intervals, for the production of the said pockets 4 and 5 and to secure the utmost strength in the finished belt, which is subjected to severe 95 strains in use. By producing the pockets in the weaving of the belts, I secure absolute uniformity in the sizes of the pockets and in their spacing from each other, whereby the belts will function much better than belts in 100 which the pockets are not produced as a part of the woven structure, but formed by stitching or at the time of applying exterior belt-

stays. As shown, though not necessarily, the pockets 4 and 5 are produced by crossing the warp threads 6 to opposite sides of the belt as shown in Fig. 6, in which the weft and 5 filler threads are represented at 7. However, if desired the belt might be woven in two strips and stitched together at regular intervals at the time of weaving for the production of the pockets, or it might be produced by placing two independently woven 10 strips face to face and stitching them together transversely after the weaving operation. As shown, the cartridge-receiving pockets 4 are reduced in diameter at the inner edge of the belt as at 8, to conform them to the reduction in size of the bullet ends of the cartridges 9, whereby the cartridges are lugged, as it were, by the fabric of the belt and so retained in place against endwise 15 movement, and whereby also they are uniformly and properly positioned in the belt at the time of their insertion thereinto in charging it. As shown, and preferably, the stay-receiving pockets 5 are woven closed as 20 at 10 at the outer edge of the belt, although this is not imperative. Within the stay-receiving pockets 5, I locate belt-stays which may assume a variety of forms, but which, as shown in Figs. 1 to 4 of the drawings, are 25 made of wire and laterally expansible for producing lateral pressure upon the cartridges 9 to assist in holding them in place in the cartridge-receiving pockets 4. These stays as thus made, consist of a pair of corresponding spring arms 11 slightly hooked inward at their outer ends and united by a shouldered loop 12 for the reception of eyelets 13 employed to close the open inner ends of the pockets 5 and retain the stays there- 30 in. It will be seen by reference in particular to Fig. 1, that the reduction in size of the inner ends of the cartridge-receiving pockets 4 to conform them to the reduced bullet ends of the cartridges 9, increases the spaces 35 between the open inner ends of the stay-receiving pockets 5 and therefore gives increased accommodation for the eyelets 13 or whatever else may be employed for closing the inner ends of the pockets 5 and holding 40 the belt-stays in place therein. The pockets 5 form a convenient, cheap and effective way of securing the belt-stays in place and locate them entirely within the belt-fabric where they are out of sight and protected, and 45 where they are prevented from cutting the threads of the belt-fabric. By the location of the belt-stays within the belt-fabric, the belt may be handled with more ease by the soldier, and operated with less friction with- 50 in the gun and with less chance of fouling, the amount of metal exposed on the outside of the belt being reduced to the minimum.

At regular intervals the regular belt-stays are replaced by special stays one of which is 55 shown in Fig. 5 of the drawings, these spe-

cial belt-stays having their inner ends extended to form long loops 14 which project beyond the ends of the cartridge bullets 15 when the cartridges are in place. These special belt-stays act as fenders to prevent the 70 bullets from being engaged at their ends, endangering the displacement of the cartridges in the belt.

Instead of employing laterally yielding belt-stays as shown in Figs. 1, 2, 4 and 5, I may, if preferred, use a sheet-metal stay 17 as shown in Fig. 7. This stay has its inner end formed with an enlarged squared portion 18 perforated as at 19 for the reception of an eyelet or rivet for securing it in place. 75

In Fig. 8, I have shown a one-piece combined sheet-metal belt-stay 20 and fender 21 extending in opposite directions from an intermediate squared portion 22 having a perforation 23 for the reception of an eyelet or rivet. 80

My improved belt, as shown, is characterized by the location of its belt-stays within stay-receiving pockets alternating with the cartridge-receiving pockets, whether the pockets are woven at the time of producing the belt or formed subsequently, my invention not being limited to the actual mode of producing the belt, nor to any one particular form of stay, nor to any one means of securing the stays in place in the stay-pockets. In a still broader view of my improved belt, it is characterized by pockets located between the cartridge-receiving pockets and employed for the reception of belt-stays and 90 cartridge-fenders, either or both. Thus I may, if desired, confine the use of some of the non-cartridge receiving pockets to the reception of fenders for preventing the cartridges from being longitudinally displaced by contact upon their bullet ends. Thus a belt-stay like that shown in Fig. 7, if secured in place with its end projecting out of the pocket instead of extending into it, would discharge all of the functions of a 100 fender. In this case the pocket would only have to be deep enough for the reception of the perforated end of the stay. 105

In Fig. 9 I have shown another modified form of belt-stay, this stay consisting of a 115 single piece of wire bent to form a long loop 24 with an eyelet-receiving eye 25 at its inner end, the ends of the wire being joined by welding, though that is not essential. This form of stay I find very easy 120 to insert into the stay-pockets in the belts, since its outer end is rounded and has no free ends to foul with the fabric.

In the modified construction shown by Fig. 10, the combined stay and fender is 125 made from a single piece of wire bent to form a belt-stay 26 and a fender 27 separated by an eyelet-receiving eye 28. The ends of the wire are welded together as shown but this is not essential. If desired 130

the ends of the wire devices shown in Figs. 4, 5 and 9 may be joined by welding or otherwise in which case the spring of the wire would still provide lateral pressure upon the cartridges.

I claim:—

1. A machine-gun feed belt having alternating cartridge-receiving and stay-receiving pockets, and laterally yielding stays located in the said stay-receiving pockets.

2. A machine-gun feed belt having woven alternating cartridge-receiving and stay-receiving pockets, the latter being woven closed at one end.

3. A machine-gun feed belt having woven alternating cartridge-receiving and stay-receiving pockets, the cartridge-receiving pockets being reduced in diameter adjacent to the inner edge of the belt, and the stay-receiving pockets being woven closed at the outer edge of the belt, belt-stays located in the said stay-receiving pockets, and means applied to the belt between the reduced ends of the cartridge-receiving pockets for closing the open ends of the stay-receiving pockets and so confining the stays therein.

4. A machine-gun feed belt having alternating cartridge-receiving and stay-receiving pockets, in combination with yielding stays located in the said stay-receiving pockets and exerting pressure upon the cartridges in the cartridge-receiving pockets for retaining the cartridges in place.

5. A machine-gun feed belt having alternating cartridge-receiving and stay-receiving pockets, in combination with stays having yielding arms located in the said pockets and exerting a constant effort to spread transversely and so exert pressure upon the cartridges in the cartridge-receiving pockets

for assisting in retaining the cartridges in place.

6. A machine-gun feed belt having alternating cartridge-receiving and stay-receiving pockets, in combination with stays, each 45 consisting of two arms united by a loop, and eyelets passed through the fabric of the belt and through the loops of the stays for retaining the same in place in the stay-receiving pockets.

7. A machine-gun feed belt having woven alternating cartridge-receiving and stay-receiving pockets, the former being reduced in size at the inner edge of the belt, and the latter being woven closed at the outer edge 55 of the belt, yielding stays located in the stay-pockets, and fastening means located between the reduced ends of the cartridge-receiving pockets and passed through the inner ends of the stays for closing the inner 60 ends of the stay-receiving pockets and for holding the stays in place therein.

8. A belt-stay for machine-gun feed belts, the said belt-stay being adapted to be inserted into a pocket in the belt and consisting 65 of a single piece of wire bent to form a loop with an eyelet-receiving eye at its inner end.

9. A combined belt-stay and fender for insertion into pockets in machine-gun feed-belts the said combined belt-stay and fender 70 consisting of a single piece of wire bent to form a loop-like belt-stay and a loop-like fender separated by an eyelet-receiving eye.

In testimony whereof, I have signed this specification in the presence of two subscribing witnesses.

FRANK H. FRISSELL.
